UNITED STATES PATENT OFFICE.

FRANK B. NOFSINGER, OF KANSAS CITY, MISSOURI.

CARTRIDGE BOX.

Application filed July 1, 1921. Serial No. 431,815.

To all whom it may concern:

Be it known that I, FRANK B. NOFSINGER, a citizen of the United States, residing at Kansas City, in the county of Jackson and 5 State of Missouri, have invented certain new and useful Improvements in Cartridge Boxes; and I do declare the following to be a full, clear, and exact description of the invention, such as will enable others 10 skilled in the art to which it appertains to make and use the same, reference being had to the accompanying drawings, and to the figures of reference marked thereon, which form a part of this specification.

15 This invention relates to cartridge boxes and particularly to a container in which the cartridges can be initially packed for commercial distribution and adapted to be subsequently utilized as a cartridge box to be attached to a belt.

20 attached to a belt.

In carrying out my invention, I prefer to provide a container of sufficient capacity to contain a considerable number of shells, and to provide a sealing flap having a fastening device interchangeably connected with a fastening device on the box to form a closure therefor, and with a fastening device on the cover to form a supporting loop through which a belt may pass so that the 25 purchaser may suspend the container from a belt so that ready access may be had to the cartridges.

In the drawings,

Fig. 1 is a perspective view of a cartridge box arranged as a container for commercial distribution of the cartridges.

Fig. 2 is a similar view showing the cover raised, with the sealing flap detached from the box, and

40 Fig. 3 is a like view showing the sealing flap folded over to form a supporting loop and secured to the cover of the box.

The invention is particularly applicable for use as a container for shot gun shells or cartridges and it is so shown in the drawings.

The box is illustrated as consisting of a bottom 1, sides 2 and 3, and ends 4 and 5 to form a substantially rectangular container. The side 2, which constitutes the front of the box, and the ends 4 and 5 are provided with flaps 6, 7, and 8 at their upper edges. These flaps may be folded over the cartridges as shown in Fig. 2, or they may be folded outwardly, as shown in Fig. 3, depending upon how the box is to be used.

Extending from the side 3, which constitutes the rear wall, is a hinged cover 9 which may be an integral part of the side 3, and said cover is provided with a sealing flap, or extension, 10, having a restricted portion or tongue 11 provided with a fastening device 12 adapted to alternately engage a complementary fastening device 13 on the front 2 of the box, or a corresponding fastening device 14 on the inner face of the cover 9. For convenience I have shown two headed members 13 and 14 constructed to conform to the well known snap or glove fastener. The members 13 and 14 are the headed members and the complementary member 12 is the socket member. When the device is to be used initially as a container for the shells for commercial distribution, the shells will be placed in the box with the flaps 6, 7, and 8 folded inwardly, as shown in Fig. 2, and the cover 9 will be folded over the top, and the sealing flap 10 will be folded down over the front 2 so that the socket 12 can engage the headed fastening member 13.

When the purchaser procures the box or case of shells and desires to use the shells, the seal 15, if one is present, can be broken, the flap 10 can be detached from the fastening 13 and the socket 12 may be folded over a band or belt 16 worn by the user and the fastener or socket 12 can be engaged with the headed member 14 to form a supporting loop, as shown in Fig. 3, whereby the box will be suspended from the belt within easy reach of the user, the flaps 6, 7, and 8 at this time being preferably turned outwardly, as shown in Fig. 3.

It will, therefore, be apparent that the 95
container will amply serve both as a ship-
ping case and a serving case or box, it being
only necessary to detach the flap 10 from
engagement with the fastener 13 and cause
the socket member 12 to engage the headed
member 14 to suspend the device from the
belt 16. It will also be apparent that the
device can be used interchangeably without
restriction and without adding or detaching
any of the parts of which it originally con- 100
sists. 105

What I claim and desire to secure by Letters Patent is:

110
1. A cartridge box comprising a container having a hinged cover and a flap on one edge thereof, a fastening device on the inner face of the cover and on one face of the box, and

- a fastening device on the flap adapted to interchangeably engage the first named fastening device.
2. A cartridge box having an open upper end, a cover connected thereto and having a flap foldable over the front of the box, means for securing the flap to the front of the box to close it, and means for sealing the flap to the inner face of the cover to provide 10 a loop whereby the box may be suspended from a belt.
3. A cartridge box having an open upper end provided with a cover, an extension on the cover foldable against the same to provide a loop, means for interchangeably securing the extension to the cover, and means for securing the extension to the front face of the box to maintain the cover in closed position.
4. A cartridge box having an open upper 20 end provided with a cover, an extension on the cover foldable against the same to provide a loop, means for interchangeably securing the extension to the cover, means for securing the extension to the front face of 25 the box to maintain the cover in closed position, and a sealing band for covering the end of the extension when it is secured to the front of the box.
5. A cartridge box having an open end, 30 a cover therefor, a fastening flap on the cover, a snap fastening element on the flap, and complementary snap fastening members on the cover and box, and adapted to be interchangeably connected by the snap 35 fastening element on the fastening flap.

In testimony whereof I affix my signature.

FRANK B. NOFSINGER.
